UNITED STATES PATENT OFFICE.

WILLIAM R. MILLER, OF BALTIMORE, MARYLAND.

TELEPHONE.

SPECIFICATION forming part of Letters Patent No. 312,492, dated February 17, 1885.

Application filed June 16, 1884. (No model.)

To all whom it may concern:

Be it known that I, WILLIAM R. MILLER, of the city of Baltimore, and State of Maryland, have invented certain Improvements in Telephones, of which the following is a specification.

This invention relates to certain improvements in the receiving-instrument of a telephone, and specifically to that class of receivers in which a sound-insulating cup adapted to fit over the ear is used.

The said invention consists in the combination, with a telephone-receiver having the usual diaphragm cover or concave plate, which is adapted to fit against the ear of the person receiving the message, of a flexible sound-insulating cup which surrounds the said plate, but is independent thereof and adapted to fit over the ear and to yield as pressure is applied to the telephone to allow of the contact of the ear with the said curved plate.

It further consists in providing the flexible elastic cup with a rigid edge composed of hard rubber or some similar material, which may be easily cleansed, and which will not become sticky or soft when handled or subjected to the action of the natural grease of the skin or that of the hair of the head with which it must necessarily come in contact in its constant use.

In the drawings forming a part hereof, Figure I is an exterior side view of the receiving-instrument of a telephone provided with my invention, which is shown as partly sectional. Fig. II is a similar view illustrating a modification in the construction of the invention.

A is the telephone-receiver, having the usual curved plate, *a*, to cover the diaphragm, and to be brought against the ear when the instrument is in use. B is the sound-insulating cup, formed of rubber or some other elastic and flexible material, having a rigid edge, *b*.

In Fig. I the rigid edge is merely a circular bead, in which the edge of the cup is inserted, and the cup is secured around the end 45 of the telephone and entirely clear of the curved plate.

In Fig. II the cup is unprovided with the bead *b*, and the cup brought below the enlarged end of the telephone, where it is fastened to the body thereof.

It will be understood that in both cases the telephone is provided with a flexible sound-insulating cup independent of the curved 55 plate *a*, which may be compressed in its application to the head to admit of the ear coming in contact with the said plate.

In this invention the adjustment of the outer edge of the cup beyond the receiver is 60 automatically accomplished in the act of bringing the ear in contact with the curved plate covering the diaphragm.

I claim as my invention—

1. In combination with a telephone-receiver having the usual curved plate to cover the diaphragm and adapted to be brought in contact with the ear, a flexible sound-insulating cup attached to the said receiver of greater diameter than the said plate, and with 70 its edge projecting beyond the end of the said receiver, substantially as and for the purpose specified.

2. In combination with a telephone-receiver having the usual curved plate to cover the diaphragm and adapted to be brought in contact with the ear, a flexible sound-insulating cup attached to the said receiver of greater diameter than the said plate, having a rigid edge which projects beyond the end of the said 80 curved plate, substantially as and for the purpose specified.

WM. R. MILLER.
